UNITED STATES PATENT OFFICE.

HENRY R. TOWNE, OF STAMFORD, CONNECTICUT, ASSIGNOR TO THE YALE
LOCK MANUFACTURING COMPANY, OF SAME PLACE.

DESIGN FOR DOORS OF POST-OFFICE LOCK-BOXES.

Specification forming part of Design No. **11,428**, dated September 23, 1879; application filed August 5, 1879.
[Term of patent 14 years.]

To all whom it may concern:

Be it known that I, HENRY R. TOWNE, of Stamford, in the county of Fairfield and State of Connecticut, have invented a new and useful Design for Metallic Doors for Fronts of Post-Office Letter-Boxes or Lock-Boxes, of which the following is a specification.

In the accompanying drawing, which illustrates my invention, A indicates a surrounding frame or margin of the door; B, a panel running across horizontally when the door is in place, and C C openings above and below the panel, both of which openings are provided with light ornamental scroll-work, that may be varied according to taste, and one of which is suitable to display a box-number, as shown.

The panel B may have letters, as shown, or any ornamental work upon it.

From the foregoing it will be perceived that the substance of my design consists in a door-frame with a panel running across horizontally, leaving open spaces above and below, within which is placed ornamental open-work or scroll-work.

Having thus described my invention, what I claim as new is—

The design for doors of post-office lock-boxes, which consists of a frame with a panel running across horizontally, leaving open spaces above and below, within which is placed ornamental scroll-work, substantially as described.

In testimony whereof I have hereunto subscribed my name.

HENRY R. TOWNE.
